FIG. 1 is a perspective view of a fish lure incorporating my design showing its scored upper surface.

FIG. 2 is a side elevation of the lure shown in FIG. 1.

FIG. 3 is a bottom plan view of the lure shown in FIGS. 1 and 2 and showing the unscored and bright polished undersurface.

FIG. 4 is an end view of the lure as shown in FIG. 3.

FIG. 5 is a longitudinal cross-section taken along the line 5—5 of FIG. 3 to show the area of double curvature as otherwise incompletely illustratable by shading in FIGS. 1, 2 and 3.

FIG. 6 is a transverse cross-section taken along the line 6—6 of FIG. 5 to show the transverse curvature at the area of maximum double curvature.

The broken lines are for illustrative purposes only.

I claim:

The ornamental design for a fish lure, as shown and described.
